193,044

DISPLAY RACK

Arthur Talmadge, New York, N.Y., assignor to United Artists Records, Inc., New York, N.Y., a corporation of Delaware

Filed Oct. 16, 1961, Ser. No. 67,093

Term of patent 7 years

(Cl. D80—10)

FIG. 1 is a front elevational view of a display rack showing my new design;

FIG. 2 is a side elevational view thereof; and
 FIG. 3 is a rear elevational view thereof.

I claim:

The ornamental design for a display rack, as shown.

References Cited in the file of this patent

UNITED STATES PATENTS

D. 184,649	Wellington	Mar. 17, 1959
D. 186,607	Hembd et al.	Nov. 10, 1959
749,494	Mason	Jan. 12, 1904